UNITED STATES PATENT OFFICE.

CHARLES T. GREENER, OF FAULKTON, SOUTH DAKOTA.

DESIGN FOR A DUSTPAN.

Application filed October 21, 1922. Serial No. 4,047. Term of patent 7 years.

To all whom it may concern:

Be it known that I, CHARLES T. GREENER, a citizen of the United States, residing at Faulkton, in the county of Faulk and State of South Dakota, have invented a new, original, and ornamental Design for Dustpan, of which the following is a specification, reference being had to the accompanying drawing, forming part thereof.

I claim:

The ornamental design for a dustpan, as shown.

CHARLES T. GREENER.
